UNITED STATES PATENT OFFICE.

ETHAN I. DODDS, OF CENTRAL VALLEY, NEW YORK, ASSIGNOR TO FLANNERY BOLT COMPANY, OF PITTSBURGH, PENNSYLVANIA.

WHEEL STRUCTURE.

1,426,157.

Specification of Letters Patent. Patented Aug. 15, 1922.

Application filed December 18, 1920. Serial No. 430,272.

To all whom it may concern:

Be it known that I, ETHAN I. DODDS, a citizen of the United States, and a resident of Central Valley, in the county of Orange and State of New York, have invented certain new and useful Improvements in Wheel Structures; and I do hereby declare the following to be a full, clear, and exact description of the invention, such as will enable others skilled in the art to which it appertains to make and use the same.

This invention relates to improvements in wheels and more particularly to a sheet metal wheel body,—one object of the invention being to construct a sheet metal wheel body from a single blank in such manner as to provide a hub portion and tubular spokes radiating therefrom.

With this and other objects in view, the invention consists in certain novel features as hereinafter set forth and pointed out in the claims.

In the accompanying drawings; Figure 1 represents a partially formed sheet metal blank; Figure 2 is a view of the completed blank; Figure 3 is a side elevation of the wheel body, and Figure 4 is a sectional view.

I first make a blank such as shown in Figure 1 by slitting a sheet of metal 1 on a number of equi-distant parallel lines 2 to form a plurality of parallel strips 3 running lengthwise of the sheet, and transverse strips 4 at respective ends of the sheet or blank. The blank is then subjected to the action of suitable dies whereby the parallel strips will be bent into semi-circular form (in cross section) as indicated at 5,—such semi-circular portions being located at respective sides of the central portion of the sheet, leaving central flat portion 6 of the strips, and extending therefrom to the transverse end strips 4.

The blank constructed as above described will be bent into cylindrical form so that the respective ends of the respective strips 4 will abut and these abutting ends will be welded together. The cylinder will then be collapsed so as to cause the end strips 4 to approach each other and form the hub portion 4* as clearly shown in Figure 4. When the

blank is collapsed as above explained, the strips 3 will be caused to be projected radially and the semi-circular portions at one side of the center of said strips to cooperate with the semi-circular portions at the other side of the center and form tubular spokes 7. The plain or flat central or intermediate portions 6 of the strips will be bent when the cylindrical blank collapsed as previously explained, and form eyes or loops 8 at the outer end of each tubular spoke.

My invention provides a substantial sheet metal wheel body made from a single blank, with tubular spokes integral with a hub portion, and with eyes or loops at the ends of the spokes which will facilitate connection of a rim to the wheel body.

Having fully described my invention what I claim as new and desire to secure by Letters-Patent, is:—

1. A sheet metal wheel body, comprising hub portions each having one-half of a series of tubular spokes integral therewith, the outer ends of the respective halves of each tubular spoke being integral with each other.

2. A sheet metal wheel body comprising hub portions, tubular spokes, each comprising two members integral respectively with the respective hub portions, integral eyes between and integral with the respective members of each spoke at the outer end of the latter.

3. A blank for a sheet metal wheel body, consisting of a single piece of metal slit and forming a plurality of parallel strips and transverse end strips, each of said parallel strips being part circular in cross section from the transverse strips to points at respective sides of the center of said parallel strips, the central portions of said parallel strips being flat.

In testimony whereof, I have signed this specification in the presence of two subscribing witnesses.

ETHAN I. DODDS.
